Primary Examiner — Jack Reickel*Assistant Examiner* — Russell Carnell Smith, Jr.(74) *Attorney, Agent, or Firm* — Michael Best and Friedrich LLP(57) **CLAIM**

The ornamental design for a television receiver as shown and described.

DESCRIPTION

FIG. 1 is a rear view of a first embodiment of a television receiver showing our new design;
 FIG. 2 is a partially enlarged rear view thereof along the lines 2-2 and 2'-2' of FIG. 1;
 FIG. 3 is a partially enlarged rear view thereof along the lines 3-3 and 3'-3' of FIG. 1;
 FIG. 4 is a partially enlarged cross sectional view cut along the line 3-3 of FIG. 2; and
 FIG. 5 is a further partially enlarged rear view thereof along the lines 5-5 and 5'-5' of FIG. 3.
 FIG. 6 is a front elevational view of the embodiment of FIG. 1;
 FIG. 7 is a left side elevational view thereof;
 FIG. 8 is a right side elevational view thereof;
 FIG. 9 is a top plan view thereof; and,
 FIG. 10 is a bottom plan view thereof.
 The broken lines illustrating portions of the television receiver form no part of the claimed design. The dot-dash broken lines illustrating boundaries of the claimed design form no part of the claimed design.

1 Claim, 7 Drawing Sheets
